ELECTRIC HEATING

Robert L. Jones, Swissvale, Pa., assignor to Edwin L. Wiegand Company, Pittsburgh, Pa., a corporation of Pennsylvania

Application September 18, 1948, Serial No. 49,904

7 Claims. (Cl. 219—34)

1

My invention relates to electric heating, and the principal object of my invention is to provide improved means for heating by radiant heat.

In the drawings accompanying this specification and forming a part of this application I have shown for purposes of illustration what I now consider to be the best mode of carrying my invention into practice, and in these drawings:

Figure 1 is a general view of the selected embodiment;

Figure 2 is an enlarged partial section on the line 2—2 of Figure 1;

Figure 3 is a section on the line 3—3 of Figure 2;

Figure 4 is a section on the line 4—4 of Figure 2;

Figure 5 is a plan view of the intermediate support means shown in elevation in Figure 4; and

Figures 6 and 7 are views indicating the manner in which two or more devices may be interconnected.

As shown in the drawings the illustrated embodiment comprises an extruded-aluminum elongated body 11 provided along its rear surface with longitudinally extending overhanging ribs 12 forming a longitudinally extending undercut channel 13 designed to receive the heads of mounting bolts 14 adjustable along the channel 13 into positions appropriate to the specific supporting means on which the heater is desired to be mounted.

The forward surface of the body 11 is substantially parabolic in cross-section but is provided along each edge with a recess 15 and a lip 16 together forming a ledge 17, and mounted in the recess of the body 11 by means of these ledges 17 are a pair of supporting plates 18 spaced from the respective ends of the body 11 and thereby dividing the recess in the forward surface of the body 11 into an extended central recess 19 and two relatively short end recesses 20.

Mounted in the recess of the body 11, extending longitudinally of the body 11, is an elongated, substantially rectilinear, radiant electric heating element 21 traversing the length of the central recess 19, supported by means of the supporting plates 18, having its ends extending into the respective end recesses 20, and provided at its ends with terminals 22 for the reception of electric conductors for connecting the element 21 to a suitable source of electric power.

For the purpose of supporting the element 21 each of the supporting plates 18 is provided with a forwardly opening recess 23 designed to receive the element 21 into desired position, and with a

2

pair of apertures 24 through which is passed a strap 25 overlying the element 21 and serving to hold the element 21 in position but nevertheless leaving the element free to move longitudinally relative to the plates 18 and straps 25, to allow for expansion and contraction of the element 21 on heating and cooling of the element 21.

To prevent undue longitudinal movement of the element 21 relative to the plates 18 and straps 25, the element 21 is provided at the plates 18 with stops 26 each comprising a length of wire having its central portion 44 encircling the element 21 and its end portions 27 disposed parallel to and welded to the element 21 and located in a slot 50 in the corresponding plate 18, thereby serving also to secure the element 21 against rotation.

With this construction, to remove the element 21 it is necessary merely to disconnect the conductors from the terminals 22 and remove the two straps 25.

However, if the length of the element 21 between the plates 18 is such that the element is likely to deform from rectilinear, preferably the element is additionally supported at one or more intermediate places, and in the present embodiment this is accomplished by providing one or more intermediate supports 28, each comprising two pieces of sheet metal 29 secured together over their central portions 45 and having their ends 30 diverging, constructed to be snapped into position with the ends 30 resting on the body ledges 17, and provided with a recess 31 designed to receive the element 21 in desired position, whereupon the element 21 is held against deviation in the direction of the opening of the recess 31 by means of a strap 32 secured in position by having its ends 33 bent through recesses 34 appropriately located in the lateral edges of the sheet metal pieces 29.

With this construction the element 21 remains free to move longitudinally to allow for expansion and contraction on heating and cooling, and to remove the element it is necessary additionally merely to remove the one or more straps 32 and snap out the one or more supports 28.

In the present embodiment the ends of the recess in the forward face of the body 11 are closed by means of end plates 35 each held in position by machine screws 36 and provided with an aperture 46 in which is mounted an insulating bushing 37 for the passage of the conductor to the respective terminal 22. However, in the event that two or more of the heaters are assembled end to end, or for any other reason it is not convenient to introduce the conductor through the end of

the heater, the body 11 is provided at each end recess 20 with an opening 33 provided with an insulating bushing 39 through which the respective conductor may be introduced through the side of the heater.

To enclose the terminals and improve the appearance the open faces of the end recesses 20 are closed by plates 40 held in position by the longitudinal recesses 15 along the edges of the forward face of the body 11.

According to the present disclosure the radiant electric heating element 21 is a metal sheathed embedded-resistor element designed to attain the appropriate temperature to radiate predominantly the particular wave length that may be desired, for example, infra red, and in approximately triangular in cross-section and located substantially at the focus of the parabolic contour of the forward face of the body 11, with one of the three faces of the element disposed substantially in a plane parallel to the plane of the two forward edges of the body 11, whereby heat from that face is transmitted directly, and only the heat from the other two faces is required to be reflected.

To improve the reflection of the heat the body 11 may be formed of anodized aluminum, but preferably as herein shown the forward face of the body 11 is overlaid with a thin sheet 41 formed of anodized rolled aluminum overlying the surface of the central recess 19, snapped into position and held in position by the longitudinal ledges 17 extending along the forward edges of the forward face of the body 11.

This separate sheet 41 provides a reflecting surface affording higher reflection and less susceptible to deterioration, results in lower cost, and inasmuch as it can be inserted at the conclusion of the manufacturing processes, avoids the possibility of the surface being damaged during the manufacturing of the heater.

To provide for assembling a plurality of heaters in side by side relation the body 11 of each heater is provided along one edge with a rib 42 and along the other edge with a recess 43 designed to receive the rib 42 of an adjacent heater.

Further, as appears from Figures 6 and 7, the structure adjacent each rib 42 or recess 43 is formed to permit a considerable variation in the relative angular positions of the heaters, whereby the heaters may be assembled in a substantially planar relation, as shown in Figure 7, or in an arcuate or circular formation, as shown in Figure 6, and therefore are susceptible of assembly in a variety of relations suitable for a correspondingly wide variety of purposes and uses.

From the foregoing it will be apparent that the illustrated embodiment of my invention accomplishes at least the principal object of my invention. However, also it will be apparent that various changes and modifications may be made, within the scope of my invention. Accordingly it is to be understood that the present disclosure is illustrative only, and that my invention is not limited thereto.

Wherefore I claim:

1. An infra-red electric heater comprising an elongated metal housing providing an elongated substantially rectilinear open sided concavity, longitudinally extending overhanging ribs along the rear surface of the housing forming a longitudinally extending undercut channel, mounting bolts having their heads disposed in said undercut channel and adjustable along said channel into positions appropriate to supporting means

on which said housing is to be mounted, a recess and a lip along each edge of the open-sided concavity, each of said recesses and lips together forming a ledge, a pair of supporting plates mounted on said ledges transversely of the open-sided concavity, said supporting plates being spaced from the respective ends of the housing to divide the open-sided concavity into an extended central recess and two relatively short end recesses, an elongated, substantially rectilinear, radiant electric heating element extending longitudinally of the central recess of the open-sided concavity and supported on said supporting plates, said heating element having its ends extending into the respective end recesses and being provided on its respective ends with terminals for the reception of electric conductors, a forwardly opening recess in each of the heating element supporting plates in which the heating element is disposed, a pair of apertures in each of said supporting plates adjacent the open ends of said recesses, and a strap extending through said recesses and transversely overlying said heating element whereby said heating element is supported in said supporting plates for lineal expansion and contraction movement.

2. An infra-red electric heater comprising an elongated metal housing providing an elongated substantially rectilinear open sided concavity, longitudinally extending overhanging ribs along the rear surface of the housing forming a longitudinally extending undercut channel, mounting bolts having their heads disposed in said undercut channel and adjustable along said channel into positions appropriate to supporting means on which said housing is to be mounted, a recess and a lip along each edge of the open-sided concavity, each of said recesses and lips together forming a ledge, a pair of supporting plates mounted on said ledges transversely of the open-sided concavity, said supporting plates being spaced from the respective ends of the housing to divide the open-sided concavity into an extended central recess and two relatively short end recesses, an elongated, substantially rectilinear, radiant electric heating element extending longitudinally of the central recess of the open-sided concavity and supported on said supporting plates, said heating element having its ends extending into the respective end recesses and being provided on its respective ends with terminals for the reception of electric conductors, a forwardly opening recess in each of the heating element supporting plates in which the heating element is disposed, a pair of apertures in each of said supporting plates adjacent the open ends of said recesses, and a strap extending through said recesses and transversely overlying said heating element whereby said heating element is supported in said supporting plates for lineal expansion and contraction movement.

3. An infra-red electric heater comprising an elongated metal housing providing an elongated substantially rectilinear open sided concavity, a recess and a lip along each edge of the open-sided concavity, each of said recesses and lips together forming a ledge, a pair of supporting plates mounted on said ledges transversely of the open-sided concavity, said supporting plates being spaced from the respective ends of the housing to divide the open-sided concavity into an extended central recess and two relatively

short end recesses, an elongated, substantially rectilinear, radiant electric heating element extending longitudinally of the central recess of the open-sided concavity and supported on said supporting plates, said heating element having its ends extending into the respective end recesses and being provided on its respective ends with terminals for the reception of electric conductors, a forwardly opening recess in each of the heating element supporting plates in which the heating element is disposed, a pair of apertures in each of said supporting plates adjacent the open ends of said recesses, a strap extending through said recesses and transversely overlying said heating element whereby said heating element is supported in said supporting plates for lineal expansion and contraction movement, and a reflector mounted in said open-sided concavity between the housing and the heating element.

4. An infra-red electric heater comprising an elongated metal housing providing an elongated substantially rectilinear open sided concavity, a recess and a lip along each edge of the open-sided concavity, each of said recesses and lips together forming a ledge, a pair of supporting plates mounted on said ledges transversely of the open-sided concavity, said supporting plates being spaced from the respective ends of the housing to divide the open-sided concavity into an extended central recess and two relatively short end recesses, an elongated, substantially rectilinear, radiant electric heating element extending longitudinally of the central recess of the open-sided concavity and supported on said supporting plates, said heating element having its ends extending into the respective end recesses and being provided on its respective end with terminals for the reception of electric conductors, a forwardly opening recess in each of the heating element supporting plates in which the heating element is disposed, a pair of apertures in each of said supporting plates adjacent the open ends of said recesses, a strap extending through said recesses and transversely overlying said heating element whereby said heating element is supported in said supporting plates for lineal expansion and contraction movement, and a reflector mounted in said open-sided concavity between the housing and the heating element, said reflector being engaged in and supported by said ledges.

5. An infra-red electric heater comprising an elongated metal housing providing an elongated substantially rectilinear open sided concavity, a recess and a lip along each edge of the open-sided concavity, each of said recesses and lips together forming a ledge, a pair of supporting plates mounted on said ledges transversely of the open-sided concavity, said supporting plates being spaced from the respective ends of the housing to divide the open-sided concavity into an extended central recess and two relatively short end recesses, an elongated, substantially rectilinear, radiant electric heating element extending longitudinally of the central recess of the open-sided concavity and supported on said supporting plates, said heating element having its ends extending into the respective end recesses and being provided on its respective ends with terminals for the reception of electric conductors, a forwardly opening recess in each of the heating element supporting plates in which the heating element is disposed, a pair of apertures in each of said supporting plates adjacent the open ends of said recesses, and a strap extending

through said recesses and transversely overlying said heating element whereby said heating element is supported in said supporting plates for lineal expansion and contraction movement.

- 5   6. An infra-red electric heater comprising an elongated metal housing providing an elongated substantially rectilinear open sided concavity, a recess and a lip along each edge of the open-sided concavity, each of said recesses and lips
10 together forming a ledge, a pair of supporting plates mounted on said ledges transversely of the open-sided concavity, said supporting plates being spaced from the respective ends of the housing to divide the open-sided concavity into
15 an extended central recess and two relatively short end recesses, an elongated, substantially rectilinear, radiant electric heating element extending longitudinally of the central recess of the open-sided concavity and supported on said supporting plates, said heating element having its ends extending into the respective end recesses and being provided on its respective ends with terminals for the reception of electric conductors, a forwardly opening recess in each of the
20 heating element supporting plates in which the heating element is disposed, a pair of apertures in each of said supporting plates adjacent the open ends of said recesses, and a strap extending through said recesses and transversely overlying said heating element whereby said heating element is supported in said supporting plates for lineal expansion and contraction movement, and means for supporting the heating element intermediate the supporting plates, said last-named means including a grooved plate having resilient ends and adapted to be snapped into place with the ends of said plate resting on said ledges.

7. An infra-red electric heater comprising an elongated metal housing providing an elongated substantially rectilinear open-sided concavity, a recess and a lip along each edge of the open-sided concavity, each of said recesses and lips together forming a ledge, a pair of supporting plates mounted on said ledges transversely of the open-sided concavity, said supporting plates being spaced from the respective ends of the housing to divide the open-sided concavity into an extended central recess and two relatively short end recesses, an elongated, substantially rectilinear, radiant electric heating element extending longitudinally of the central recess of the open-sided concavity and supported on said supporting plates, said heating element having its ends extending into the respective end recesses and being provided on its respective ends with terminals for the reception of electric conductors, a forwardly opening recess in each of the heating element supporting plates in which the heating element is disposed, a pair of apertures in each of said supporting plates adjacent the open ends of said recesses, a strap extending through said recesses and transversely overlying said heating element whereby said heating element is supported in said supporting plates for lineal expansion and contraction movement, and means for supporting the heating element intermediate the supporting plates, said last-named means including a grooved plate having resilient ends and adapted to be snapped into place with the ends of said plate resting on said ledges.
